UNITED STATES PATENT OFFICE.

EDMUND C. MORGAN, OF CHICAGO, ILLINOIS, ASSIGNOR TO AMERICAN MORGAN COMPANY, OF CHICAGO, ILLINOIS, A CORPORATION OF SOUTH DAKOTA.

MINING AND LOADING APPARATUS.

1,116,358.

Specification of Letters Patent.

Patented Nov. 3, 1914.

Original application filed November 10, 1896, Serial No. 611,603. Divided and this application filed July 1, 1914. Serial No. 348,331.

To all whom it may concern:

Be it known that I, EDMUND C. MORGAN, a citizen of the United States, residing in the city of Chicago, county of Cook, and State of Illinois, have invented certain new and useful Improvements in Mining and Loading Apparatus, of which the following is a specification.

The present application is a division of my co-pending application, Serial No. 611,603, filed November 10, 1896, for an improvement in apparatus for mining coal.

Referring to the accompanying drawings, Figure 1 represents a longitudinal sectional elevation of a mining machine embodying my invention; Fig. 2 is a detail view of a portion of the cutters of the mining machine; Fig. 3 is a plan view of the entire mining machine, including the cutting mechanism; Fig. 4 is a sectional elevation of the mining machine, taken on the line 4—4 of Fig. 3, looking in the direction of the arrows; Fig. 5 is a transverse sectional elevation taken on the line 5—5 of Fig. 3, looking in the direction of the arrows; Fig. 6 illustrates the cutting mechanism mounted in a different position from that shown in Figs. 1, 2 and 3; Fig. 7 illustrates the function of the side plates when a pillar in the mine chamber is to be removed; Fig. 8 is a sectional elevation of a part of the mining machine taken on the line 8—8 of Fig. 3, looking in the direction of the arrows; Fig. 9 is a side elevation of mechanism which may be used for operating the various clutches and gearing which are shown in plan view in Fig. 3; Fig. 10 is a front elevational view of Fig. 9; and Fig. 11 is a plan view of the construction shown in Fig. 9.

The same part is designated by the same reference sign wherever it occurs throughout the several views.

I will first describe the construction, function and mode of operation of my improved coal-mining apparatus, particular reference being had to Fig. 1, wherein reference sign A designates the framework, upon which is mounted a supplemental frame as well as several other operative parts of the apparatus, as will more fully hereinafter appear. The framework should be of such form, size, proportion and ar-

rangement as to properly accommodate the several parts of the apparatus.

The framework A is mounted on suitable traction wheels B, B, as shown, whereby the machine may be transported from one part of a mine to another, or readily advanced to its work or retracted therefrom, or moved slowly forward during the mining operation. These traction wheels may be driven in any suitable or convenient manner, or by any suitably arranged mechanism adapted for such purpose. I will presently describe an illustrative arrangement for accomplishing this purpose.

Suitably mounted upon the framework of the machine is a motor C, preferably electric, of the series-wound type, arranged and adapted to operate the several devices hereinafter referred to, as will presently be more fully described. The motor C is preferably of the series-wound type, so as to operate the propelling mechanism at a speed in proportion to the load on the motor. The current may be supplied to the electric motor C through any suitable conductor D, which may extend from the source of power along the floor of the mining machine direct to the electric motor, or it may be arranged as shown in the drawing and as will be more fully explained hereinafter.

A gear E, preferably a worm, is shown in Fig. 1 arranged to be driven by the motor C, the worm E being mounted loosely on the armature shaft C of the motor. The gear E meshes with and drives a gear F, preferably a worm wheel, mounted on a shaft G which is arranged to extend transversely across the machine and which carries suitable gears at the outer ends thereof. These latter gears are preferably sprocket gears engaging the sprocket chains 200, as shown in Fig. 3. These sprocket chains are geared to the traction wheels B, B, so that when the shaft G is rotated the entire mining machine may be moved in one direction or the other.

It should be understood that I prefer to connect the sprocket gear driving mechanism between each of the outer ends of the transverse driving shaft G and the rear traction wheels B, B, as shown in Fig. 3. Any suitable and well-known form or arrangement of clutch K, such as a jaw clutch

or a cone clutch, may be employed for throwing the driving gear of the traction wheels into and out of operation, at will. This clutch K, which is shown in sectional elevation in Fig. 1 and in plan in dotted lines in Fig. 3, may be controlled by a suitable operating lever, as shown at K' in Figs. 9 and 11. The lever K' may be pivoted to a pedestal 218 mounted on the main frame A, as shown in Fig. 9. By suitably actuating or reversing the motor C, the traction wheels may be driven in the desired direction to advance the mining machine from one part of the mine to another, or to advance the mining machine to its work or to withdraw the mining machine therefrom, or to move the mining machine slowly forward during the mining and loading operation. The speed of the motor, if the motor is a series-wound electric motor, may be automatically regulated according to the load, the machine advancing slowly when meeting with considerable resistance, and being moved faster when the load on the motor is reduced. By suitably operating the clutch K, the driving gearing for the traction wheels may be thrown into or out of action at will.

It should be understood that by means of the traction wheels, the entire mining machine may be moved to the point where the cutters, hereinafter described, are placed in readiness to break down coal from the mine wall, and that the machine may be fed forward as fast as the coal is broken down and removed. However, since the traction wheels form a yielding means for advancing the machine, slipping of the traction wheels may occur on the mine floor when the tendency is to overtax the capacity of the cutters by their encountering particularly hard material. Where the material can be easily cut, the traction wheel driving mechanism alone may be sufficient to resist any backward slipping of the mining machine. When coal very difficult to cut is reached, it may in some mines become important and necessary to brace the mining machine against the resistance offered by the coal to the cutters, and to provide positive means for slowly advancing the cutting mechanism whenever that is desired. In order to accomplish this purpose, I mount upon the frame A in any suitable or convenient manner a pair of screw rods M, M, as shown in Fig. 3, each being provided in its near end with a pivotal connection to a pair of bracing arms N, N, in toggle joint fashion, each arm being in turn pivotally connected loosely to an anchor shoe O, as shown in Fig. 1. The members of each pair of shoes O may, if desired, be suitably serrated on their engaging surfaces, and respectively arranged to engage the walls of the room or the floor and roof, as clearly shown in Fig. 1.

From this construction and arrangement, it will be seen that when an endwise pressure is exerted upon the screw rods M in a direction opposite the forward path of the machine, the toggle arms N will be put under stress to force the anchor shoes O away from each other and into engagement with the floor and roof or the walls of the mine chamber, thereby securing and firmly anchoring the entire machine against rearward movement. If the pressure is continued to be exerted longitudinally of the screw rods, the entire mining machine is advanced or fed forward slowly, away from the position of the anchor shoes and in a direction to advance the forward limit of operation of the coal-cutting mechanism. In practice, when the anchor shoes are arranged to engage the floor and roof of the mine chamber, I prefer to employ two or more screw rods, and hence also two or more pair of toggle rods M and shoes O, for the reason that by suitably arranging one pair of these anchoring and feeding devices on one side of the machine, and another pair on the opposite side, as clearly indicated in Fig. 3, I am enabled to straighten the machine in case its course departs from a straight line. Therefore, control of the forward movement and the direction of the path of travel may be easily accomplished by throwing one or the other set of anchoring and feeding devices into or out of action, as occasion may require.

I will now describe a suitable and efficient construction and arrangement for exerting the pressure above mentioned longitudinally upon the screw rods M, whereby the machine is first anchored and then fed forward to advance the forward limit of operation of the cutters. In the particular form shown, I provide a gear P on the shaft C' of the motor C, as shown in Fig. 1. The gear P meshes with the gear L, which in turn meshes with the gear L', and the latter meshes with the gear Q. This train of gearing is shown in Figs. 1 and 3. A shaft S is suitably mounted on the upper part of the main frame of the mining machine, to extend transversely across the same, as shown in Fig. 3. The transverse shaft S carries a gear T, which meshes with a suitable gear U, preferably a worm, mounted on the shaft R. An internally threaded nut or sleeve 14 is mounted in a suitable bearing connected to the main frame A, so that said nut will engage a screw-threaded rod M. It should be understood that there is one of these internally threaded nuts or sleeves 14 on each of the screw rods M, M. By rotating said nuts or sleeves 14 in one direction or the other, the desired pressure is exerted upon the screw rods in one direction or the other to effect an anchoring of the machine and the feeding thereof, or to effect a release of

the machine. Inasmuch as the arrangement of gearing for rotating the nuts 14 is the same for both the screw rods M, I will specifically describe the arrangement for only one screw rod. The nut 14 carries or has formed integrally therewith two gears 15 and 16, as shown in Fig. 1. Upon a suitably and conveniently mounted shaft 17, as shown in Fig. 3, are loosely mounted two gears 18 and 19, the gear 19 being of relatively large diameter with respect to the gear 18. The gear 19 meshes directly with the gear 16 of nut 14, as shown in Figs. 1 and 3, while gear 18, which is of relatively small diameter, engages and drives the gear 15 through an intermediate idler gear 20. From this construction, it will be seen that when the gear 19 is idle and gear 18 is acting, the sleeve 14 will be slowly rotated in one direction, namely, in the direction to effect a longitudinal pressure on the screw rod M, to cause the anchor shoes O to grip the roof and floor or side walls of the room and to effect a feeding of the machine forward. If the gear 18 is idle and the gear 19 is acting, the sleeve 14 is more rapidly rotated in the opposite direction, and an endwise movement of the screw rod in the opposite direction is effected, thereby releasing the anchor shoes O.

Any suitable and well-known form of clutch 21, as shown in Fig. 1, may be employed to throw either gear 18 or gear 19 into or out of action at will. A worm gear 22, mounted on shaft 17, as shown in Fig. 3, is arranged to engage a worm 23 on the transverse shaft S. By means of a suitable and conveniently arranged clutch 24, as shown in Fig. 3, the mechanism for actuating the anchoring and feeding means on one side of the machine may be thrown into or out of action at will. The clutch 24 may be omitted, if desired, however, and the rod S made continuous, so that whenever the motor C is operated, motion will be transmitted from the shaft R to the worm gearing U, T, and thence to the transverse shaft S and the worms at the ends thereof. In this manner, whenever the motor C operates, the transverse shaft S and the short shaft 17 are continuously rotated. The clutches 21, when in central position, will not effect rotation of either the gears 18 or the gears 19. It is therefore obvious that the mechanism for actuating the anchoring and feeding means at the sides of the machine may be thrown into or out of action at will, independently of each other, by means of the clutches 21. It is also obvious that if the clutch 21 at one side of the machine is left in central position, and the clutch 21 on the other side of the machine is thrown in, so as to actuate the gear 18, the machine at that side will be moved forward, slowly while being braced by the anchoring shoes O on

both sides of the machine. In this way the forward movement or direction of travel of the entire mining machine may be easily controlled. The loose pivotal connection between the toggle links N and the shoes O will, of course, permit gradual turning of the mining machine while being advanced, and while the bracing toggle mechanism remains in operative position. While I have shown the screw rods M, in Fig. 1, as being supported on the main frame by means of the bearings 14, which may be of any desired length, additional supports extending from the rear portion of the main frame in the form of brackets may be provided if desired. Such brackets may be rigidly connected to the main frame and extend rearwardly therefrom, with bearings at their upper ends encircling the screw rods M, particularly where the threads of such screw rods are squared or rectangular in longitudinal cross section. From the foregoing description, it will be seen that when the machine has been advanced to the limit of the feed screws M, the said screws may be moved quickly in the opposite direction to advance the anchoring shoes to a point closer to the machine, by reversing the clutches 21. In this manner, a fresh grip of the anchoring shoes is secured, after which the feeding action may be repeated. Any suitable and well-known provision may be made, if desired, for preventing the upper toggle links N from falling below a limited distance when the screw rods M are moved forwardly and the shoes O released from the roof of the mine chamber.

Upon the front end of the framework of the main frame A, I mount a frame or platform 25, to be held by the main frame substantially parallel to the floor of the mine, slightly above the same or partly resting thereon. The platform 25 is therefore mounted in such relation that it will occupy a horizontal plane, or a plane substantially parallel to the floor of the mine, so as to readily enter a floor kerf or horizontal kerf cut at the base of a mine wall by another machine. The frame or platform 25 may be detachably connected to the lower front end of the main frame, as indicated at 202 in Figs. 1 and 3. I prefer to rigidly attach the middle section only of the platform 25 to the main frame A, by means permitting the entire platform to be detached from the main frame. I prefer to construct the platform 25 of three sections, 41, 42 and 43, detachably bolted together as shown at 44, 44', in Fig. 3. In order to withdraw the entire mining machine from the mine wall, it may be desirable or necessary, in some instances, to remove the sections 41 and 43 of the platform and fold them onto the section 42, so as to facilitate the transportation of the machine from place to place. Inasmuch as the

platform is nearly as wide as the mine chamber, such folding of the platform will avoid undue friction against the walls of the mine. The shortening of the width of the front 5 portion of the mining machine facilitates the withdrawal thereof at considerably greater speed than when the side sections 41, 43, together with the side plates attached thereto, are left in position.

10 In the present embodiment of the invention, the means for breaking down coal from the mine wall is combined with the means for removing the broken down coal. An under kerf and side kerfs are first produced 15 by another machine, and then the mining machine herein disclosed is brought into a position with the platform 25, extending into the under kerf. The cutters 101 are then operated to break down the body of 20 coal above the under kerf, after which the scoop 58 is operated to take up the material and deliver it onto the carrier 88, shown more clearly in Fig. 1. It is desirable to first snub off the lower corner of the wall of 25 the undercut coal, because in some instances the weight of the coal above will then have opportunity to break down the coal onto the platform, after which it may be broken up by the cutters, if necessary, and then loaded 30 into mine cars. The work of loading the coal into the mine cars may be carried on intermittently with respect to the breaking down operation.

The breaking down apparatus comprises 35 a supplemental frame 57, which is pivoted at 56 to the main frame, and is supported at its forward end on the roller bearings 81. It will thus be seen that the supplemental frame 57 is pivotally mounted on 40 the main frame for lateral movement thereon. The forward portion of the supplemental frame 57 carries the mechanism for controlling the reciprocating movements of the cutters and the tilting or rocking there- 45 of in vertical planes. In order to effect the reciprocating movement of the cutters 101 mounted on the support 58, the shaft 70, shown in Fig. 1, must be rotated, because it carries the gears 71, as shown in Fig. 10. 50 These gears 71 mesh with the rack bars 68, 68, mounted to slide in the guides 69, which are rigidly attached at the sides of the trough 87.

The means for controlling the reciproca- 55 tion of the cutters 101 comprise a bevel gear 78, at one end of the shaft 70, supported by an extension from the supplemental frame, as shown in Fig. 3. The bevel gear 78 meshes with two additional bevel gears 75 60 and 76, between which is mounted a clutch 77 on a shaft 74. The clutch 77 may be operated by means of a lever 222', as shown in Fig. 3, or by means of a rearwardly ex- 65 tends lever 222, as shown in Fig. 9. When the clutch 77 is thrown in one direction, the

support for the cutters 101 will be moved forwardly, and when the clutch 77 is moved in the opposite direction the cutters 101 will be retracted.

The source of power for operating the cutters to tilt them vertically and to move them laterally, and to reciprocate them, comprises the electric motor C, which, whenever it operates, continuously rotates the gear L and consequently also the hollow shaft 61, 75 through the universal joint 60 and the sliding connection 62. Preferably, this sliding connection comprises a rod, square in cross section, fitting into a corresponding opening in the hollow shaft 61. On the hollow shaft 61 is mounted a gear 72, as shown in Fig. 3. The hollow shaft 61 is suitably mounted in bearings connected to the supplemental frame, so that said hollow shaft will be free to rotate but will be kept from sliding either way in such bearings longitudinally. The gear 72 being in mesh with the gear 73, which is fixed to the shaft 74, motion is transmitted to the latter whenever the electric motor C is operated. The bevel gears 75 and 76, being mounted loosely on the shaft 74, will not rotate until the clutch 77 is thrown in one direction or the other.

In order to control the rocking or tilting of the support 58 for the cutters 101, the said support is pivoted at 59, 59, to the outer ends of the rack bars 68, as shown in Fig. 3. These pivotal connections may comprise pintles or gudgeons fixed to the support 58 and extending into bearings at the outer ends of the rack bar 68. To one of these pintles is fastened a bevel gear 67, which meshes with two bevel gears 64 and 65 on the shaft 63. Between the bevel gears 64 and 65 is mounted a clutch 66, which may be operated by means of the short lever 211', shown in Fig. 3, or by means of the long rod 211, shown in Fig. 9, mounted on the supplemental frame in the bearings 226 and 227. The gears 64 and 65 being mounted loosely on the shaft 63, do not rotate therewith until the clutch 66 is thrown in one direction or the other, whereupon the support 58, with the cutters 101 thereon, will be tilted either up or down in a vertical direction. The shaft 63 is mounted in bearings extending from the rack bar 68 at that side, and cannot be moved longitudinally. The shaft 63 is provided with an inner extension 63', which is preferably square in cross-section and fits into a corresponding opening in the forward end of the hollow shaft 61. This sliding connection between the rod 63' and the hollow shaft 61 permits the control of the tilting of the support 58 to be retained, whatever the forward position of the cutters may be, within the limits of the operation of the mining machine. Whenever the hollow shaft 61 is rotated, motion is transmitted to the rods 63' and 63, and

whenever the clutch 66 is thrown in, the gear 67 will be actuated to tilt the support 58 on its pivots 59, 59.

The apparatus for controlling the lateral movements of the cutters 101 comprises bevel gears 84 and 85, loosely mounted on the shaft 74. A clutch 86 is also mounted on the shaft 74 between the gears 84 and 85. Meshing with the gears 84 and 85 is a horizontal bevel gear 83, which is connected to the upper end of a short vertical shaft mounted in bearings connected to the supplemental frame 57, as shown in Fig. 9. At the lower end of the shaft carrying the bevel gear 83 is a spur gear 83', which meshes with the arcuate rack 82. This arcuate rack is mounted on the main frame at 82', 82', as shown in Figs. 3 and 4. The clutch 86 may be operated by means of a short lever 220', shown in Fig. 3, or by means of a long lever 220, as shown in Fig. 9. The lever 220 is connected to a shaft 219 mounted in vertical bearings attached to the supplemental frame. When the clutch 25 86 is thrown in one direction, the spur gear 83' travels on the arcuate rack 82 to move the support 58 and the cutters 101 thereon laterally in a corresponding direction, and when the clutch 86 is thrown to the opposite side the support 58 and the cutters 101 will be moved laterally in the opposite direction.

Preferably the support 58 for the cutters 101 is in the form of a scoop, so that after sufficient material is broken down for removal this scoop may be so operated as to take up a load and move it backwardly, and then dump it onto the carrier 88. In the supplemental frame 57, a trough or way 87 is mounted as shown in Fig. 1. This trough is upwardly inclined from the forward end thereof toward the rear, and its forward end is so arranged with respect to the scoop as to receive the coal therefrom when the scoop is tilted backwardly a sufficient distance. The forward end of the trough or chute 87 is preferably provided with an inclined cross piece 212, as shown in Fig. 1, to direct the material from the scoop onto the belt conveyer or carrier 88, which delivers the material into a mine car, as shown in Fig. 1. As illustrative of the idea, I have shown an endless belt, band or carrier 88 arranged upon rollers shown mounted on the shafts 89 and 90; respectively arranged at the upper and lower ends of the chute or trough 87.

The apparatus for controlling the operation of the carrier 88 comprises a gear 92 fixed to the shaft 90, as shown in Fig. 9. The gear 92 meshes with another gear 91 above the same. The gear 91 is fixed to a shaft 93, to which is also fixed the bevel gear 94, as shown in Fig. 3. The bevel gear 94 meshes with the bevel gear 95 which is

mounted loosely on the shaft 74. A clutch 96 on the shaft 74 may be operated by a short lever 224', shown in Fig. 3, or by means of a long lever 224, as shown in Figs. 9 and 11. The long lever 224, when operated, turns a vertical shaft 223 which is mounted in vertical bearings attached to the supplemental frame. When the clutch 96 is thrown into engagement with the gear 95, the latter is rotated and transmits motion to the gears 94 and 91, the latter then transmitting motion to the gear 92 and the shaft 90. So long as the clutch 96 remains in operating position, the belt conveyer 88 will continue to operate, provided the motor is operating to continuously rotate the hollow shaft 61 and the gears 72, 73 and the shaft 74.

The cutters 101 may be adjusted to different locations on the support 58. For this purpose, holes 301 may be provided in the cutters 101, and holes 302 in the support 58, for receiving bolts 300, as shown in Fig. 3. When the support 58 is in the form of a scoop, I prefer to mount the cutters on the bottom of the scoop, as shown in Figs. 1, 96 2 and 3, so that the forward ends of the cutters will project only a sort distance beyond the forward edge of the scoop. When the cutters are thus adjusted, they will interfere but little, if at all, with the scooping operation, because as shown in Fig. 2, when the scoop is moved over the platform its forward edge will occupy a position near the upper surface thereof, and therefore be capable of scooping up all the coal in its 100 forward path of movement. When, however, the cutters are to be used mainly for breaking down the material, or when it is desired to first break down the material and then readjust the cutters before the scooping operation is performed, the cutters may be adjusted to such a position as shown in Fig. 6. The cutters are here shown snubbing off the lower corner of the wall of the undercut coal, thereby changing the horizontal kerf into a V-shape. Such a V-shape kerf facilitates the subsequent breaking down of the coal, and in some instances affords the upper body of coal an opportunity to break down of its own weight. This 115 snubbing operation is accomplished automatically by power-actuated mechanism under the control of manually-operated levers, as hereinbefore explained. Whenever desired, the snubbing cutters 101 may be unbolted and easily removed, or moved to a new position. The snubbing requires the expenditure of only a small amount of power, which can readily and easily be applied through the reciprocating mechanism.

Obviously, when the cutters 101 are in snubbing position, as shown in Fig. 6, the support for said cutters may be advanced and retracted by power-operated means, and the operation repeated as often as desired,

and at various angles, by moving the supplemental frame laterally in either direction from the position shown in Fig. 3. It is therefore evident that the cutters 101 are in reality reciprocating tools for breaking down the material above an undercut or lower kerf in a mine wall. If desired, the reciprocation of the cutters 101 in various angular directions may be carried on for breaking down all the material above the undercut up to the roof of the mine chamber, so as to leave sufficient clearance for the advancement of the entire mining machine or of a kerf-cutting mining machine into the mine wall. The snubbing cutters are capable of this operation, particularly when the support 58 therefor is made of sufficient length, and the cutters are adjusted in their extreme forward positions, as shown in Fig. 6. It should also be understood that the reciprocating tools 101 may in some instances be used to break up material broken down in large blocks. Therefore, in such cases where the coal is dislodged by its own weight, the reciprocating tool may be used to break it up into pieces within the capacity of the scoop and conveyer to handle.

In some instances, the platform 25 may be left entirely detached, and the bottom of the kerf used as a platform for the scoop. In such event, if the cutters dig into the coal floor when the scooping operation is performed, the cutters 101 may be adjusted to their ineffective positions, as shown in Fig. 11, and the bottom of the scoop made horizontal.

Inasmuch as the reciprocating tools 101 partake of the vertical turning movements of the support 58, and the lateral movements of the supplemental conveyer, it will be seen that the cutting tools may be adjusted to various angles in vertical planes and to various angular positions laterally, so as to command the entire cross-sectional area of the room and provide sufficient clearance for the continued advancement of the mining machine disclosed herein, or of another mining machine used for the purpose of producing additional and deeper kerfs in the mine wall. This is obvious from an inspection of Figs. 1 and 6, from which it will be seen that the slicing off of the under side of the body of coal above the under cut may be continued up to the roof of the mine chamber. It should also be observed that the carrier, by moving with the supplemental frame, always remains in alinement with the scoop or in the same vertical plane therewith, no matter what the lateral position of the scoop may be. Furthermore, since the pivot 56 is near the rear end of the supplemental conveyer, the carrier will continue to deliver the coal to the mine car for all lateral positions of the scoop, and the scoop need not be brought back to central

position each time it delivers a load to the carrier.

In case I employ an electric motor C for operating the several parts of the machine as above described, and such a form of motor, for many practical reasons, I prefer to use, it becomes a matter of convenience to supply the operating current thereto in a manner that will permit of the advancement of the machine farther and farther into the bed of coal, as the latter is broken down within the limits of the kerfs produced by another machine. As an illustrative form of operative means accomplishing this desired object, I have shown a suitable electric conductor D leading from the motor C to a reel 102, where this conductor makes suitable sliding electrical connection with the inner end of a flexible connector 103, insulated and wound on the reel 102. The latter is suitably mounted to rotate in bearings on the main frame, so that the insulated flexible conductor 103 may be wound upon this reel or unwound therefrom, as the case may be. Electrical connection between the conductor D and the conductor 103 may be made in any suitable and well-known manner, as will be readily understood by persons skilled in the art. The source of electric power is connected to the conductor 103, which, through the lead D, supplies the current to the motor C, the return circuit being made through the rails on which the mine cars 100 move. Of course, it will be understood that the conductors 103 and D are the ordinary type of insulated conductors, and that the connections are such that short-circuiting or grounding is prevented except for the desired return circuit.

By providing means for winding or un-winding the conductor 103 from the reel 102 synchronously with the advancing or retracting movements of the machine, the current is supplied to the motor for actuating the several parts of the apparatus, as above explained. The reel 102 may be conveniently rotated in the following manner: A gear 104, mounted on the axle of the reel, as shown in Fig. 1, engages and is driven by a worm 105 mounted on the shaft R. From this construction and arrangement, it will be readily seen that when the motor C is operated in one direction or the other, the conductor 103 is reeled up or paid out accordingly. When the electric motor C operates the traction wheels of the mining machine to transport the latter to the end of the mine room or chamber, where the machine is to perform its breaking down and loading operation, the conductor 103 is paid out as the machine advances. When the mining machine is transported to another part of the mine, the conductor 103 will be taken up in accordance with the retracting of the machine. Even when the mining machine

advances slowly forward during the breaking down operation, the reel mechanism pays out the conductor 103 in accordance with such movement. However, it may be desirable to move the machine forward intermittently. The mechanism shown is such that when the scoop and conveyer are operated, the shaft R is also rotated. I therefore prefer to mount the worm wheel 104 loosely on the shaft 213, and provide a cone clutch 214 operated by the lever 215 for connecting or disconnecting at will the shaft R to the reel 102, as shown in Fig. 11. By means of this arrangement, the reel may be operated to take up slack in the conductor 103 even when the mining machine is not being moved over the mine floor. The lever 215, as shown in Fig. 11, may be located in a convenient position for actuation by a single operator standing on the truck platform.

In the practical operation of mining, it is important to form rooms or chambers parallel with each other and a distance apart about equal to the width of the rooms, thus leaving intervening walls or pillars of coal of substantially the same thickness as the width of a room, as supports for the coal above. After the particular portion of the mine being worked has been exhausted, it is desirable to mine the coal forming the pillars. In such cases, it is necessary to undercut only the pillars, as the side cuts have already been made. This undercutting may be performed by a separate machine, but the breaking down of the coal, and removing the same, may be done by means of the machine disclosed herein, particularly when side plates 120, 120 are bolted or otherwise secured to the platform 25, as shown in Fig. 3. The side plates 120 may, in some instances, be detachably connected to the main frame, but I prefer to detachably connect them to the platform 25, so that when the sections 41 and 43 are detached, the side plates 120 may be removed at the same time. In some instances, I prefer to use only one side plate, particularly where the mining machine herein disclosed is used as a long wall mining machine, in which event an under kerf produced by a separate machine will be the only kerf in the mine wall. However, if an additional kerf is produced in vertical position, both side plates could be retained in position. When the mining machine herein disclosed is being used to break down a pillar, the side plates act as collectors or guides to prevent the material as broken down from spreading off the platform 25. In the same way, when the machine is used as a long wall mining machine, the outside side plate maintains the material on the platform within the field of operation of the scoop.

In place of the single universal joint 60 shown in Fig. 3, an additional universal

joint 216 may be provided, as shown in Fig. 11. A sleeve 217 is then connected to the universal joint 216 for receiving the sliding rod 62, which is preferably square in cross section. With this arrangement, a greater degree of horizontal movement of the scoop may be obtained, although a single universal joint, as shown at 60 in Fig. 3, is sufficient for most practical purposes.

In order that the mining machine and loading apparatus herein disclosed may be controlled by a single operator, the various levers for operating the clutches may be extended to a position within reach of an operator on the truck platform A, toward the rear of the machine and to one side of the pivoted supplemental frame. For throwing in the clutch K, a lever K', pivoted at 218 to the main frame, is provided. By means of this lever, the worm gearing E, F and 25 the shaft G may be connected to the motor shaft or disconnected therefrom whenever desired. It will be noticed that in Figs. 9, 10 and 11, the gearing and clutches for operating the same are located in a vertical plane, so as to give a greater degree of lateral movement to the supplemental conveyer. In Fig. 3, this gearing is shown in a horizontal plane, for the sake of clearness. In order to secure the lateral movement of the supplemental conveyer, the lever 220 is moved in a horizontal plane in one direction or the other, depending upon the direction of lateral movement of the supplemental conveyer desired. In order to effect the reciprocating movement of the cutters and of the scoop carrying the cutters, the lever 222 is moved in a horizontal plane, in one direction to secure the forward movement of the cutters and the scoop, and in the other direction to secure the retracting movement thereof. In order to set the conveyer or carrier in continuous operation, the lever 224 is moved horizontally toward the supplemental conveyer and left there. In order to tilt the scoop or rock the same on its pivot, the slide bar 211 is pushed forward or drawn back, accordingly as the scoop is to be tilted up or down. It should be observed that the slide rod 211 is supported in bearings 226 and 227, which are mounted on the rack bar 68 at that side of the supplemental conveyer where the clutches are located.

I have herein shown mining mechanism comprising cutters mounted on the scoop, together with means for receiving and taking up the coal that is broken down during the mining operation and conveying it away from the place where it falls; the mechanism herein shown also being intended to carry the broken down coal to a vehicle such as a mine car, for taking it out of the mine. But the specific features of construction and mode of operation incident to the particular devices for receiving, pick-

ing up and conveying away the coal I do not herein claim; preferring to have the claims herein relate to the devices which pertain to mining, and to the combination 5 with a mining machine capable of performing the functions of that herein described, of a receiving and carrying-away mechanism for clearing away the broken down material, coming within the claims herein.

10 The novel and patentable features of structure which are incident to the specific form of mechanism for picking up the coal and carrying it away I have made the subject-matter of claims in my copending application, Serial No. 607,753, filed February 10, 1911, as a division of my application Serial No. 611,603, filed November 10, 1896. The novel and patentable methods of mining disclosed herein and in my copending application Serial No. 611,603 I have made the subject-matter of claims in my copending application Serial No. 629,246, filed May 24, 1911, for an improvement in a system of mining coal. In my copending application Serial No. 210,174, filed May 28, 1904, I have shown and described and presented specific claims for conveying mechanism in combination with breaking-down mechanism of the sort known to the mining engineer as "pick machines", these being devices capable of giving rapid, powerful, percussive blows produced by one of several well known agencies. And in my copending application Serial No. 293,004, filed December 22, 1905, I have shown and described and presented specific claims for such a "pick machine", in combination with a conveyer entering a kerf at the base of the mine wall, and also in combination with 30 kerf cutting mechanism. While I do not herein specifically claim the subject-matter claimed in my copending application Serial No. 210,174, filed May 28, 1904, and in my copending application Serial No. 293,004, filed December 22, 1905, I broadly claim such subject-matter herein because the cutters for breaking down the coal are provided with means for giving them a reciprocating movement as well as movements 40 in vertical and horizontal planes, and loading apparatus extending into the kerf is provided comprising means below the plane of action of the mining tool for receiving the material as it is dislodged.

50 In the machine disclosed in this present application, the kerf-cutting mechanism is omitted, said machine being used to break down the coal or other material from a mine wall and load such material into mine cars after an undercut or a sidecut and an undercut, or a plurality of vertical kerfs and an undercut have been produced by a separate machine operating in advance of the breaking down and loading apparatus disclosed herein. It should be observed, how-

ever, that the breaking down mechanism and the loading apparatus are combined in a unitary structure, and so also, when the platform is used, it becomes a part of a unitary structure. Therefore, after a kerf or kerfs 70 have been produced by one or more separate machines, the parts herein disclosed cooperate with each other in the nature of an excavating machine to break down the coal from the mine wall and load it into mine 75 cars.

While I have disclosed one form or embodiment of my invention herein, it will be understood by those skilled in the art that various changes in the details and arrangement of parts might be made without departing from the spirit and scope of my invention as defined by the claims.

What I claim and desire to secure by Letters Patent of the United States, is:

1. A mining and loading machine comprising a frame, a forwardly projecting platform extending beyond the frame adapted to enter a previously formed kerf in the mine wall, breaking-down mechanism on 90 said frame for breaking down the material above the kerf on to said platform, and loading apparatus on said platform for removing said broken-down material from said platform.

2. In mining apparatus, the combination with a portable framework, of a horizontal platform connected to said framework so as to be carried thereby and extending from the forward end thereof near the floor of a 100 mine, and a reciprocating tool for breaking down the material onto said platform.

3. In mining apparatus, the combination with a portable framework, of a horizontal platform carried by said framework and extending from the forward end thereof near the floor of a mine, a mining tool for breaking down the material from the mine wall to said platform, and means for resisting any tendency toward backward movement of said framework and platform during the operation of said mining tool.

4. In mining apparatus, the combination with a mining machine, of a platform extending therefrom and adapted to enter the previously made kerf in a mine wall to receive the material broken down above said undercut, and means for propelling the said mining machine together with the platform connected thereto to cause the latter to act as a conveyer for transporting material away from the mine wall.

5. In mining apparatus, the combination with a portable framework, of a reciprocating tool mounted on said framework, means for operating said reciprocating tool to break down sections of the mine wall, a platform carried by said framework for receiving the material as it falls by gravity, and means for propelling said framework 130

together with the platform and the broken down material on the latter away from the wall.

6. In a mining machine, the combination with a reciprocable mining tool, of means for operating said tool, a power-actuated mechanism for directing the movement of said tool in various directions, and means for controlling said power-actuated mechanism.

7. In mining apparatus, the combination with a reciprocating tool for breaking down material from a mine wall, of power-actuated means for giving said reciprocating tool vertical and horizontal movement, and means for removing and carrying away from the mine wall the broken down material.

8. In mining apparatus, the combination with a main frame, of a supplemental frame pivotally mounted on said main frame, a carrier mounted on said supplemental frame, a motor connected to said supplemental frame for swinging the same about its pivot, a mining tool mounted on said carrier, and means for operating said tool.

9. In a mining machine, the combination with a frame, of a carrier pivotally mounted upon said frame, a motor connected for moving said carrier about a pivotal connection on said frame, a tool support mounted upon said carrier, means for rocking said tool support about its connection with said carrier, and means for reciprocating said tool support relatively to said carrier.

10. In a mining machine, the combination with a frame, of a carrier pivoted to said frame for laterally swinging movements, power-actuated mechanism for swinging said carrier, a mining tool supported by said carrier, and means for operating said tool.

11. In a mining machine, the combination with a main frame, of a supplemental frame pivoted for horizontal movement on said main frame, a reciprocating mining tool connected to said supplemental frame and movable therewith, means for reciprocating said mining tool, a pivotal connection between said mining tool and said reciprocating means, and apparatus for controlling the swinging of the supplemental frame and the rocking of said mining tool.

12. In mining apparatus, the combination with a mining tool, of mechanism for operating said mining tool, a frame for carrying said mining tool and said operating mechanism, a platform connected directly to said frame and capable of entering an undercut in unmined material in the mine, and a vertical plate connected to said platform.

13. In mining apparatus, the combination with a frame, of substantially vertical plates spaced apart and connected to said frame, and means carried by said frame for break-

ing down material in the mine wall, said plates occupying a position adjacent the lateral faces of the material being mined.

14. The combination of a mining machine, and a sectional platform detachably but rigidly connected to said mining machine so as to be carried thereby.

15. The combination of a mining machine, and a platform detachably but rigidly connected thereto to receive the broken down material when said platform is in a horizontal kerf in a mine wall.

16. In mining apparatus, the combination with a main frame, of a supplemental frame, a mining tool mounted on said supplemental frame for lateral movement, and means for moving away from the mine wall the dislodged material toward the rear of said main frame into position for loading mine cars.

17. In a mining machine, the combination of means for breaking down a mine wall adjacent incisions therein, and a device in position during the operation of said breaking down means for confining the broken down material to a limited space.

18. In mining apparatus, the combination with a truck, of a conveyer mounted for lateral movement on said truck, and a reciprocating tool movable vertically near one end of said conveyer.

19. In mining apparatus, the combination with a reciprocating tool for breaking up material, of means for taking up the material and carrying it away, and a laterally movable frame for carrying both the reciprocating tool and said conveying means.

20. In mining apparatus, the combination with a reciprocating tool movable in a vertical plane, of means for taking up the broken down material and moving it away from the material operated on by said reciprocating tool, a laterally movable frame for carrying said reciprocating tool and said conveying means, and means for moving said frame to adjust said reciprocating tool to various angular positions.

21. In mining apparatus, the combination with means for breaking down material from a mine wall, of a plate capable of extending along a mine wall to confine broken down material to a limited space, and means for conveying away the broken down material from said limited space.

22. The combination with a mining machine, of a platform connected thereto, and side plates, said mining machine comprising means for breaking down material onto said platform between said side plates.

23. In a mining machine, the combination with a main frame, of a conveyer mounted for lateral movement on said main frame and extending forwardly from the same, power means for operating the conveyer and

moving it laterally, breaking-down means mounted for lateral and vertical movement to command a space bounded by the floor, roof and sides of the mine chamber, and power means for operating said breaking-down means.

24. A mining machine comprising means for breaking down a section of a mine wall formed by an undercut and a side cut, in combination with loading means extending into the undercut and comprising a conveyor, and means to confine the material broken down within the operating space of the loading means by preventing said material from spreading over the mine floor.

25. In mining apparatus, the combination with a frame mounted for horizontal movement, of a platform extending into a kerf to receive the broken down material, reciprocating means mounted above said platform to break down the material thereon, and means for removing the material from said platform.

26. In a mining machine, the combination with a portable frame, of a platform capable of extending into a kerf in a mine wall to a position near the inner end thereof, breaking-down means, and means for operating said breaking-down means to operate on the face of the mine wall back of the forward edge of said platform.

27. In combination, a supporting frame, a rearwardly extending conveyor on said frame, a reciprocating tool mounted upon said frame, and means for feeding the frame forward.

28. In combination, a supporting frame, a rearwardly extending conveyor on said

frame, and a universally adjustable reciprocating tool mounted on said frame.

29. In combination, a supporting frame, a rearwardly extending conveyor on said frame, a reciprocating tool mounted on said frame, and means for adjusting said frame laterally.

30. In a coal loading machine, the combination with breaking-down means, of means adapted to extend into an undercut in the coal and receive the same when broken down, and means for conveying the broken down coal away from the receiving means.

31. In a mining machine, the combination of receiving means adapted to extend into an undercut in a mine wall, of snubbing cutters, and means for operating said snubbing cutters above said receiving means when the latter is in position in the undercut.

32. In a mining apparatus, a frame, reciprocating breaking-down means mounted for vertical and horizontal adjustment on said frame, and power means for advancing said frame.

33. In a mining machine, the combination with a portable frame, of a reciprocating mining tool mounted thereon, and means for feeding said frame forwardly and controlling the direction of forward movement thereof.

In testimony whereof I have signed my name to this specification, in the presence of two subscribing witnesses, on this 27th day of June, A. D. 1914.

EDMUND C. MORGAN.
